(71) Applicant: **Unger Marketing International, LLC**,
Bridgeport, CT (US)

(72) Inventor: **Anthony Sgroi, Jr.**, Wallingford, CT
(US)

(73) Assignee: **UNGER MARKETING
INTERNATIONAL, LLC**, Bridgeport,
CT (US)

(**) Term: **15 Years**

(21) Appl. No.: **29/594,840**

(22) Filed: **Feb. 23, 2017**

Related U.S. Application Data

(63) Continuation of application No. 29/544,787, filed on
Nov. 6, 2015, now Pat. No. Des. 798,996, and a
continuation of application No. 29/487,620, filed on
Apr. 10, 2014, now Pat. No. Des. 742,997.

(57) **CLAIM**

The ornamental design for a water purification media device,
as shown and described.

DESCRIPTION

FIG. 1 is a top perspective view of the water purification
media device according to the present disclosure;
FIG. 2 is a first side view of the water purification media
device of FIG. 1, the opposite sides being a mirror image
thereof;

FIG. 3 is a second side view of the water purification media
device of FIG. 1, taken ninety degrees from the view of FIG.
2, the opposite sides being a mirror image thereof;
FIG. 4 is a top view of the water purification media device
of FIG. 1; and,

FIG. 5 is a bottom view of the water purification media
device of FIG. 1.

The broken lines in the drawings illustrating boundaries that
form no part of the claimed design.

1 Claim, 5 Drawing Sheets
